OSCAR THOMSEN, SR., OF FLEMINGTON, NEW JERSEY, ASSIGNOR TO FORAN BOILER COMPANY, INC., OF FLEMINGTON, NEW JERSEY, A CORPORATION OF NEW JERSEY

BOILER

Application filed March 24, 1932. Serial No. 600,860.

This invention relates broadly to vapor generators and more particularly to boilers. In one of its aspects, the invention relates to the tubes in which vapor is generated in generators and the arrangement thereof. In another of its aspects, the invention relates to improvements in certain component elements of a vapor generator, specifically the circulating column to which the tubes are connected.

One object of the invention is to provide a vapor generator of increased efficiency. To this end, a rapid circulation of the vapor from its point of generation to the vapor dome is effected. This is attained, preferably, by the provision of a plurality of circulating columns extending between the liquid base and the vapor dome, which circulating columns are divided into two separate passages, one of which is in communication with the liquid base and the other of which is in communication with the vapor dome, and of a plurality of reversely bent tubes which affords communication between the respective passages so that the flow of vapor generated in the tubes is unimpeded by the presence of liquid delivered to the subsequent superimposed tubes.

It is also an object of the invention to provide tubes and circulating columns therefor, which is practical from the standpoint of ease and cheapness of manufacture and convenience in installation and use.

These and other objects of the invention and the means for their attainment will be more apparent from the following detailed description taken in connection with the accompanying drawing, illustrating one embodiment as applied to a boiler or steam generator by which the invention may be realized, and in which:

Figure 1 is a view in side elevation, showing a series of tubes mounted upon a circulating column in accordance with this invention, separate passages of which columns are connected to a water base and steam dome, fragmentary parts of which are illustrated;

Figure 2 is an enlarged view in elevation, looking from the left of Figure 1;

Figure 3 is a detail view on an enlarged

scale, partly in elevation and partly in section, taken in the planes indicated by the broken line 3—3 of Figure 2;

Figure 4 is a view looking from the left of Figure 3; and

Figure 5 is a transverse sectional view taken in the plane indicated by the line 5—5 of Figure 4.

While the invention has been illustrated and will be described as applied to the generation of steam, it will be readily apparent that it is equally applicable in any situation where vapor is to be generated from a liquid and while the terms "water base", "steam dome", "water" and "steam" are used throughout the description, they are to be considered as illustrative only of the application and the term "steam dome" is broadly used to denote any reservoir or container for any vapor, such as a pipe, drum or other vessel, and the term "boiler" is intended to denote any vapor generator.

The generator or boiler employing this invention may take any desired form and, therefore, details of the same are not illustrated. Suffice it to say that the boiler may have a water base of any convenient form, a fragmentary portion of which at one side of the boiler is indicated at 10. Similarly, a fragmentary portion of a steam dome or its equivalent is indicated at 12.

Extending upwardly from the water base 10 is a water leg, indicated at 14, to which may be secured a plurality of circulating columns and to which a series of boiler tubes 16—18 are connected. Similarly, the steam dome is shown as provided with a depending leg 20 with which the upper end of the circulating column, in accordance with this invention, is in communication in any convenient fashion. Slip nipples are illustrated as such connecting means. The circulating column may be disposed on one or both sides of the boiler as will be understood. Since their disposition forms no part of the invention, only one circulating column is illustrated and will be described.

Circulating columns forming the subject matter of this invention are shown as formed of two circulating column members 22 and 100

30 each having separate passages, as illustrated clearly in Figure 2. Thus, extending upwardly from the water base 10-14 is a circulating column section or member 22 enlarged at its lower end, as at 24, to receive a slip nipple 26 by which communication is had with the water leg 14. This member 22 will be referred to as the water column passage or generally as a circulating column member. 5
 10 It is provided with a downwardly directed flange or ear 25, suitably slotted, by which it is bolted or otherwise conveniently secured to the water base and by which a tight joint with the slip nipple is attained. The water 15 column passage extends upwardly to the upper end of the boiler and is provided at its upper end with an ear 28 by which it is secured to a cooperating ear 29 on a companion depending steam conducting circulating column member 30, as by a removable connection shown as a bolt 32. The depending circulating column member 30 is identical with the water column circulating header except that it is in reverse position when installed 20 in the boiler, and similar reference characters are affixed thereto. Similar reference characters have been applied to its connection both above and below so that the description of the fastening of the one member will suffice for the pair. Thus these two companion 25 members are interchangeable and the manufacturing of the circulating columns is facilitated and simplified.

The enlarged end or head 24 at one end of 30 the circulating column 22 or 30 is offset therefrom or laterally overhangs the column a distance substantially equal to the width of said column. The head 24 is hollow across its full double width and consequently accommodates the enlarged port 26. The hollow or chambered portion 24 is defined by a closing side wall which follows around the port and nipple 26 and then turns downwardly and forms one side wall of the narrow water column 22 or 30. However, the front wall or face of the chamber 24 projects beyond the nipple and port 26 and forms the flat rectangular ear 29 which laps over and forms securing means with the ear 28 provided on 35 the other end of the inverted and cooperating circulating column section. Thus the two anchorage ears 28 and 29 with bolt 32 there-through occupy that space defined by the overhanging head 24 terminating in the flat front corner 29. It follows, therefore, that the narrow end and ear 28 of the other column fits up into and behind the space defined by the flat front ear piece 29 to produce a circulating column of inverted sections forming 40 a closely joined rectangular member 22, 30 and that a plurality of these assembled pairs can be set one against the other to produce a closed wall to house or enclose the steam generating tubes 16, 18.

65 The boiler tubes 16-18 are reversely bent

or substantially hairpin shaped as shown in the drawing and a series of them are arranged one above the other on the circulating column 22, 30. The lower arms 16, of each of these boiler tubes, are in connection with the water passage 22, while the upper arms 18 are in connection with the steam passage 30. Thus, in effect, the column section 22 is filled with water, as well as the lower halves 16 of the respective tubes. It is in these lower parts 16 that the steam is generated and flows through the upper tube halves 18 into the steam passage in the other column section 30 through which the steam passes into the steam dome unimpeded by water. Any water of condensation which may occur or find its way into the steam passage 30 will be returned to the water column 22 and/or water base 10 through the lowest tube, since it will be observed that the arm 18 of the lowest boiler tube communicates with the steam passage 30 at the very end or lower-most part of the passage. Similarly, steam cannot be trapped in the water passage 22 because the lower arm 16 of the uppermost boiler tube is connected with the uppermost end of the water passage and must find its way to the steam passage 30 and hence to a steam dome. Here, again, it will be noted that the holes for the ends of the boiler tubes, formed in each circulating column section or member 22 and 30, are correspondingly placed so that the two sections are interchangeable. The elongated hollow portion of each circulating column member 22 and 30 has a single row of circulating tube openings in at least a part of its length and preferably the entire length of the elongated hollow portion is a single row of tube openings as shown in the drawing. The hollow portions of each circulating column member 22 and 30 which carry a single row of tube openings are placed side by side and secured together in this position to form a combined rectangular circulating column.

100 It will thus be seen that a boiler tube and circulating column construction has been provided which assures a positive one way circulation, which increases the efficiency of steam generation and permits of the use of 105 interchangeable parts.

110 Various modifications will occur to those skilled in the art in the configuration and disposition of the sectioned circulating column of this invention as well as its incorporation into a boiler or vapor generator or other use to which it may be put, and no limitation is intended by the phraseology of the foregoing description or illustrations in the accompanying drawing, except as indicated in the appended claims.

What is claimed is:—

1. As an article of manufacture, a circulating column member for vapor generators comprising an elongated hollow portion hav-

ing an enlarged end, the enlarged end being offset laterally and substantially double the member width and adapted to form a rectangular combined circulating column with 5 a second inverted member, an opening in said enlarged end for connection with either a liquid base or a vapor dome, a plurality of holes in said member in the elongated hollow portion to receive tubes, securing means at the 10 enlarged end for securing the member to either a liquid base or a vapor dome, connecting means inwardly of the enlarged end and forming a rectangular end for connection with the end not enlarged of a companion member, and connecting means at the remote 15 end for connection with the enlarged end of a companion member.

2. As an article of manufacture, a circulating column member for vapor generators comprising an elongated hollow portion having an end enlarged substantially double the width of the hollow portion and adapted to form a rectangular combined circulating column with a second inverted member, an 20 opening in said enlarged end for connection with either a liquid base or a vapor dome, said opening being at least as large as the passage through the elongated hollow portion and directed laterally thereof for lateral 25 connection with a liquid base or a vapor dome, a plurality of holes in the elongated hollow portion to receive tubes, securing means at the enlarged end for securing the member to either a liquid base or a vapor 30 dome, connecting means inwardly of the enlarged end and forming a rectangular end for connection with the end not enlarged of a companion member, and connecting means at the remote end for connection with the enlarged end of a companion member.

3. A vapor generator comprising a steam dome, a water base, a plurality of circulating columns placed closely adjacent each other, each circulating column including a 45 pair of identical circulating column members one being inverted relatively to the other, each member having an elongated hollow portion, an end on each elongated hollow portion enlarged substantially double the width 50 of the hollow portion and adapted to form a rectangular combined circulating column with the inverted second member, an enlarged opening directed laterally in said enlarged ends for connection with the steam dome and 55 the water base, and securing means at each end of said circulating column members whereby said members are secured together.

4. As an article of manufacture, a circulating column member for vapor generators comprising an elongated hollow portion having an enlarged hollow end substantially double the width of the elongated hollow portion and extending laterally to one side of the member and adapted to form a rectangular 60 combined circulating column with a second

inverted member, an opening in said enlarged end for connection with either a liquid base or a vapor dome, a plurality of holes in said member to receive tubes, and securing means at each end whereby said member may be 70 secured to an inverted identical circulating column member.

5. As an article of manufacture, a circulating column member for vapor generators comprising an elongated hollow portion having an enlarged hollow end substantially double the width of the elongated hollow portion and extending laterally to one side of the member and adapted to form a rectangular combined circulating column with a second inverted member, an opening in said enlarged end for connection with either a liquid base or a vapor dome, said opening extending laterally from the enlarged hollow end, a plurality of holes in said member to receive tubes, and securing means at each end whereby said member may be secured to an inverted identical circulating column member.

6. As an article of manufacture, a circulating column member for vapor generators comprising an elongated hollow portion having an enlarged hollow end substantially double the width of the elongated hollow portion and extending laterally to one side of the member and adapted to form a rectangular combined circulating column with a second inverted member, an opening in said enlarged end for connection with either a liquid base or a vapor dome, said opening being at least 90 as large as the passage in the elongated hollow portion, a plurality of holes in said member to receive tubes, and securing means at each end whereby said member may be secured to an inverted identical circulating column member.

7. As an article of manufacture, a hollow circulating column member for vapor generators comprising an elongated hollow portion having an enlarged hollow end substantially double the width of the elongated hollow portion and extending laterally to one side of the member and adapted to form a rectangular combined circulating column with a second identical circulating column member in inverted position, an opening in said enlarged end for connection with either a liquid base or a vapor dome, said opening extending laterally from the enlarged hollow end and being at least as large as the passage through the elongated hollow portion, a plurality of holes in said elongated hollow portion to receive tubes, securing means at the enlarged end for securing the member to either a liquid base or a vapor dome, a first connecting flange projecting from the enlarged end of the circulating hollow member and along the side of the elongated hollow portion, said connecting flange being flush with the wall of the circulating column member and with the 110

enlarged hollow end forming a rectangular end for connection with the end not enlarged of a companion member, and a second connecting means projecting from the remote 5 end for connection with a connecting flange on a companion member corresponding to the first connecting flange to secure two circulating column members together to form a rectangular circulating column.

10. 8. A vapor generator comprising a steam dome, a water base, a plurality of circulating columns placed closely adjacent each other, each circulating column including a pair of identical circulating column members one 15 being inverted relatively to the other and forming a rectangular circulating column, each circulating column member having an elongated hollow portion, circulating tubes connecting together the inverted circulating 20 column members of each circulating column, the end of each circulating column member having a substantial width, the end of each circulating column member having a laterally directed enlarged opening for connection 25 with the steam dome and the water base, the opening being substantially larger than the cross sectional area of a circulating tube, and securing means for securing the circulating column members together.
30. 9. A circulating column for a vapor generator comprising a pair of identical circulating column members one being inverted relatively to the other and forming a rectangular circulating column, each member having an 35 elongated hollow portion, circulating tubes connecting together the hollow portions of each circulating column member forming a

single circulating column, the end of each circulating column member having a substantial width, the end of each elongated hollow portion having a laterally directed enlarged opening adapted to be connected with a steam dome and a water base of a vapor generator, the opening being substantially larger than the cross sectional area of a circulating tube, and securing means for securing the circulating column members together. 75

10. A circulating column for a vapor generator comprising a pair of identical circulating column members one being inverted relatively to the other, each member having an elongated hollow portion having a single row 80 of circulating tube openings in at least a part of its length, the hollow portion of each inverted circulating column member having a single row of circulating tube openings being positioned side by side to form a rectangular 85 circulating column, circulating tubes secured in the circulating tube openings and connecting together the hollow portions of each circulating column member forming a single circulating column, an end of each circulating 90 column member having a substantial width, said end of each circulating column member having a laterally directed enlarged opening adapted to be connected with a steam dome and a water base of a vapor generator, the opening being substantially larger than the cross sectional area of a circulating tube, and securing means for securing the circulating 95 column members together.

In testimony whereof I affix my signature. 100
